UNITED STATES PATENT OFFICE.

JOHN Q. CLARKE, OF CRAWFORDSVILLE, INDIANA, ASSIGNOR TO WILLIAM W. CLARKE, OF NELSON, CALIFORNIA.

VENTILATED HOUSE.

Application filed September 18, 1925. Serial No. 57,202.

This invention relates to a portable house in which suitably to keep small chickens, especially those hatched in large numbers in incubators, the invention having reference 5 more particularly to a metallic sanitary brooder house of the knock-down type. An object of the invention is to provide a simple and well lighted and ventilated house which shall be of such construction as to not 10 only house and retain young fowls, or young animals, but shall protect them against attack by hawks and other predatory birds or fowls and animals.

Another object is to provide an improved 15 capacious ventilated house which shall be of such construction as to be adapted to be compactly shipped in knock-down condition and to be readily set up for use when needed, and which shall be of light weight to 20 permit the house to be shifted from place to place as may be desired.

A further object is to provide an improved brooder house structure which shall insure adequate ventilation for the health of 25 the occupants and protect them against im- 30 mal climatic conditions that might result in pecuniary loss besides suffering of the housed fowls.

A still further object is to provide an improved brooder house structure which shall be adapted for keeping the floor region 35 of the house ventilated and in sanitary condition, permit graduated ventilation generally and permit heating of the house when required, which structure shall be durable and economical in use.

With the above-mentioned and other objects in view, the invention consists in a portable house having improved ventilating 40 means including a conduit for conducting foul air from the floor of the house, and a novel ventilating window to admit fresh air into the upper portion of the house while excluding birds and insects; and the invention 45 consists also in the parts and the combinations and arrangements of parts as herein-after particularly described and further defined in the claims appended hereto.

Referring to the drawings,—Figure 1 is a 50 perspective view on a small scale indicating the general nature of the invention; Fig. 2 is a vertical central sectional perspective view illustrating the interior of the brooder house and the ventilating system thereof; 55 Fig. 3 is a detached perspective view of the

ventilating window, on an enlarged scale; and Fig. 4 is a horizontal section of portions of the ventilating apparatus in the roof of the house, on an enlarged scale.

Similar reference characters in the different figures of the drawings indicate corresponding elements or features of construction herein referred to in detail.

The invention as applied to a brooder house comprises a base ring 1 which preferably is composed of L-section iron and for convenience is shown as being circular but obviously may have an octagonal or other form in plan. A sheet metal vertical side wall 2 is suitably secured to the base ring, and a conical roof 3 is suitably secured to the top of the wall. The wall has a doorway 4 in one portion thereof which is provided with a door 5 which may be adapted to swing either outwardly or inwardly. The wall has a suitable number of window frames 6 in each of which a lower window sash 7 is secured, a ventilating window sash 8 being arranged upon the lower sash and connected thereto by means of suitable hinges 9. Each window frame has side plates 10 and 11 that extend inwardly and preferably are tapered so that the top is broader than the bottom of the plate. A window screen 12 is arranged in the window frame at the outer side of the upper sash. The tops of the side plates have notches 13 therein to receive latch bars 14 that are pivoted to the upper portion of the upper sash, permitting the sash to afford graduated ventilation. A yoke is provided for each window and comprises a bar 15 having arms 16 and 17 connected to its ends and pivoted to the side plates 10 and 11 respectively, to tie the side plates together and to prevent the upper sash from dropping down when unlatched, or to be swung upward to release the sash and permit it to be lowered entirely from the side plates.

The apex of the roof 3 has a ventilator 100 structure therein which comprises a tubular body part 18 that is vertically secured in a suitable opening in the roof and has a hollow conical top 19 supported by brackets 20 so as to cover the upper end of the body part 105 and shed rain water but permitting air to pass from the top of the body part into the surrounding atmosphere. The body part 18 extends downward a suitable distance below the apex of the roof and a ventilator tube 21 110

is arranged under the roof and is connected to one portion of the body part, another similar ventilator tube 22 preferably being provided and connected to the opposite portion of the part 18. The tubes 21 and 22 are designed to conduct foul air from the interior of the house and preferably have vertical tubes 23 and 24 connected to the lower ends thereof respectively and extending downward to within a short distance from the ground or floor upon which the base ring may be located so as to conduct foul air from the floor area. The body part 18 has an annular bottom 25 which supports a section of draft pipe 26, which preferably extends upward beyond the upper ends of the ventilator tubes to receive the usual flue pipe of the stove which obviously is to be used in the house when required to heat the house sufficiently for health and comfort of the brood.

In practical use the upper sashes are adjusted to admit more or less air as may be desired. Usually the heating stove remains in the house throughout the year and its draft pipe practically closes the pipe section 26, so that a strong draft occurs upward through the ventilator tubes, carrying away the foul air from the floor, the heated air from the stove passing from the top pipe section 26 tending to induce up-draft through the ventilator tubes and the body part 18 of the ventilator. In the warm season the stove or its draft pipe may be removed to permit the warmer air naturally rising in the house to pass out through the pipe section 26. The metal roof becomes warm in summer time especially when exposed to the sun, and heat is radiated to the tubes 21 and 22 so that air becomes heated in the tubes and naturally rises and causes up-draft through the vertical tubes. The upper sashes set at an inclination and the side plates prevent rain and snow from being driven into the

house while admitting into the upper interior of the house sufficient ventilating air, and the screens prevent entrance of annoying insects and also predatory birds and animals, the wall of the house and its door and windows preventing the entrance of rats and other destructive animals.

What is claimed as new is:

1. A ventilated house including a circular wall and a conical roof thereon, ventilator windows in the wall having each a screened upper sash hinged at its bottom to swing inwardly and deflect atmospheric air upwardly towards the roof, and a ventilator structure secured in the upper portion of the roof and extending downward therefrom, the structure having an annular bottom, a ventilator tube connected at its upper end with the ventilator structure beneath the roof, the lower end of the tube being open adjacent to the bottom of the wall, and a pipe section connected to the inner edge of said annular bottom and extending upward beyond the upper end of the ventilator tube.

2. In a ventilated house, the combination with a wall and a conical metal roof thereon, of a hollow tubular ventilator body secured in the apex of the roof and extending downward therefrom, the body having an annular bottom, a ventilator tube having a terminal portion connected with the ventilator body above said bottom, the tube extending down towards the bottom of said wall, and a pipe section connected to the inner edge of said annular bottom and extending upward in said body past said terminal portion, the ends of said section being open, to cause partial vacuum in said body and induce upward currents through said tube.

In testimony whereof, I affix my signature on the 12th day of September, 1925.

JOHN Q. CLARKE
